METHOD AND APPARATUS FOR MAINTAINING TEMPERATURE AND HUMIDITY CONSTANT

Theophil Eichmann, Berne, Switzerland, assignor to George B. Scarlett, Kennett Square, Chester County, Pa.

Application October 8, 1948, Serial No. 53,394

7 Claims. (Cl. 62—4)

1

This invention relates to methods and apparatus for maintaining temperature and humidity constant; and the nature and objects of the invention will be readily recognized and understood by those skilled in the arts involved in the light of the following explanation of the preferred method and the steps thereof of my invention and of the detailed description and explanation of the accompanying drawing illustrating what I now consider to be a preferred improvement and arrangement of apparatus of my invention capable of operation to carry out and perform such preferred method.

This invention relates particularly to a method of keeping the temperature and the humidity constant in the air of a cold chamber by means of a refrigerating machine. The method according to the invention consists in the feature that the refrigerating machine, as well as an air-cooled condenser and a water-cooled condenser connected in parallel therewith, are controlled by a thermostat and a hygrometer in such a way that the evaporator and the water-cooled condenser are set in operation by the thermostat, and, after attainment of a predetermined temperature and release by the thermostat, the evaporator and the air-cooled condenser are set in operation by the hygrometer, until the thermostat interrupts the action of the hygrometer and switches on the cooling operation again insofar as the predetermined value of the humidity of the air has not already been reached previously by the hygrometer.

Apparatus of my invention for carrying out the method thereof is illustrated more or less schematically by way of example in the accompanying drawing.

Referring to the drawing, the apparatus of the example includes an air-cooled condenser 1 in a passage 15, and a water cooled condenser 2 connected in parallel therewith by the hot, compressed gas supply line 1a and the condensate return line 1b. An evaporator 3 is, in this instance, located in the passage 15 and is connected with the suction intake side of a compressor 4 by the suction or return gas line 3a. As will be understood by those skilled in the art, both condenser 1 and evaporator 3 are in heat exchange relation with the air of the chill room. The compressed gas discharge or pressure line 2a connects the discharge side of compressor 4 with condensing coil 2b of condenser 2. The compressed gas line 1a to the air cooled condenser is connected to and receives hot, compressed gases from the discharge line 2a from the compressor 4 just in advance of the condenser 2.

2

The water cooled condenser 2 is supplied with cooling water by a supply line 1a, and water is discharged from the condenser by the discharge line 1b, in the usual manner of the conventional water cooled condensers familiar to the art. The cooling evaporator 3 receives condensed refrigerant for expansion therein, through a condensate supply line 3b which has its intake end in a condensate reservoir or tank 16, in accordance with conventional practice. Condensed refrigerant is supplied to the reservoir 16 by a supply line 2c connected to the discharge end of condensing coil 2b and discharging into reservoir 16. The condensate line 1b from the air cooled condenser 1 is, in this instance, connected into line 2c for the return of condensate from air cooled condenser 1 to the reservoir 16.

An electrically controlled solenoid type valve 5 is connected into the condensate line 2c between condenser 2 and the condensate reservoir 16 for controlling flow of condensate through this line. An electrically controlled solenoid type of valve 6 is connected into the condensate return line 1b between the air cooled condenser 1 and the reservoir 16 for opening or shutting off this line to flow of condensate therethrough.

In the cooling operation or cycle of the apparatus, the cooled vapors are sucked out of the evaporator 3 by compressor 4 through the vapor return line 3a, compressed by the compressor, condensed in the condenser 2 and then returned to the evaporator 3 through line 2c, reservoir 16 and line 3b, all in accordance with the usual refrigerating or cooling cycle familiar in the art.

In the operation of the refrigerating cycle the valve 5 in line 2c is open while the valve 6 in line 1b from the air cooled condenser 1 is closed. In the heat pumping or air conditioning operation of the apparatus, the valve 6 is opened while the valve 5 is in a partially closed or throttled position, so that the hot, compressed gases from the compressor 4 are discharged through line 1a through the air cooled condenser 1 and returned as condensate through line 1b to the reservoir 16.

The compressor 4 is power driven by an electric motor 17 in the usual manner, this motor being in this instance supplied with operating current through a three-phase power circuit comprised by the circuit lines R—S—T. In this circuit there is located and connected the usual motor controlling and protecting contactor unit 18, as will be familiar to those skilled in the art. The operation of the compressor and the operation and control of the solenoid valves 5 and 6 is effected automatically through an electrical control system which includes a thermostat 8 associated

with a control or master relay 9, and a hygrostat 12 associated with a control relay 11. The thermostat 8 and the hygrostat 12 are, of course, located in the chill room.

The thermostat 8, which as shown schematically may be of any of the well-known mercury tube types, is connected with the power circuit R—S—T by the controlling circuit line 8a, and is connected to the master relay 9 by a circuit line 8b for control of the cooling cycle. The master relay 9 controls a circuit therefrom to the solenoid valve 5 which includes the circuit line 5a. The relay 9 also includes and controls a circuit for effecting operation of the contactor 18 for controlling operation of the compressor 4 by the motor 17, such circuit being constituted by the circuit line 18a. And the relay 9 also includes a controlling circuit for operating the fans 10. This latter circuit is constituted by a circuit line 10a.

The relay 11 is conditioned for control by the hygrostat 12 only when the temperature of the chill room has been lowered to a predetermined temperature by operation of compressor 4, condenser 2 and evaporator 3 as a conventional cooling or refrigerating machine. When, however, the predetermined temperature controlled by the thermostat 8 is reached, the functioning of the thermostat effects operation of control relay 11 for control by the hygrostat 12 of the predetermined humidity conditions in the chill room.

The relay 11 has a control circuit 12a therethrough in connection with hygrostat 12 and thermostat 8 including a circuit line 12b from relay 11 to the neutral lead 10b. Relay 11 is supplied with current by a circuit line 11b. The relay 11 controls a circuit therethrough which connects by a circuit line 11c with the circuit 10a to the fan 10. The relay 11 also includes and controls a circuit therethrough which connects by a circuit line 18b with the circuit 18a to motor controlling contactor unit 18. The relay 11 also includes and controls an actuating circuit through the solenoid operated valve 6 in the condensate return line 1b from the air cooled condenser 1. This circuit includes a circuit line 6a from relay 11 to one side of solenoid valve 6 and to circuit line 6b from the other side of the solenoid to the neutral lead 10b.

The system may include an electric motor driven circulating fan or fans 10 included in a circuit constituted by a circuit line 10a between relay 9 and one side of the motors 10, and a connection from the opposite side of the motor of a fan 10 to the neutral lead 10b.

An automatic pressure controlled valve 7 is connected in the cooling water supply line 7a to the condenser 2 for controlling flow through that line. This valve 7 is controlled by a pressure line 7c from compressor 4 in a manner such that upon a predetermined fall of pressure in compressor 4 the valve 7 is actuated to close lines 7a and thus stop consumption of water by the water cooled condenser 2, while at another predetermined higher pressure the valve is actuated to open position for supply of cooling water to the condenser in the normal refrigerating operation.

The air cooled condenser or air heater 1 is provided of such relatively large dimensions that during the operation of the system to include the heat pumping cycle the liquefying or condensing temperature is preferably 5° C. lower than the temperature in the water cooled condenser 2. As a result of this fall of pressure resulting from

the lower condensing temperature as referred to above, the water valve 7 is caused to operate to close the cooling water supply line 7 to the condenser 2. And in addition, because of this fall of final pressure, the power required by the compressor is also reduced.

With the system of the invention functioning solely as a refrigerating or cooling cycle to lower the temperature in the chill room or other space to be refrigerated, the thermostat 8 has functioned to actuate the master relay 9 to condition the various circuits controlled thereby to cause operation of the compressor 4, fan or fans 10 and the electrical shut-off valve 5, so that, liquid refrigerant is forced from condenser 2 through line 2c, reservoir 16 and line 3b into the evaporator 3. The cold evaporation gases are then drawn back through line 3a to the suction side of compressor 4 for recycling, in the usual manner. In the system when so operated, valve 5 is open while the valve 6 in the condensate return line 1b from the air cooled condenser 1 is closed, thus effectively shutting off operation of that condenser to function as a heating element.

When, however, the predetermined temperature has been reached in the cold room, the thermostat 8 switches off the master relay 9 and, through the circuits as above described, conditions the control relay 11 for operation by the hygrostat 12 upon an increase in the humidity of the cold room. When the predetermined humidity is reached and hygrostat 12 effects operation of control relay 11, the system is then caused to function partially as a heat pump to condition of the air in the cold room. The switching on of relay 11 by hygrostat 12 closes the circuit 6a—6b through solenoid valve 6 to cause that valve to open. At the same time valve 5 has been caused to close or partially close, so that hot, compressed gases then circulate through line 1a to air cooled condenser 1, and through that condenser to heat the air therein, with the resulting condensate being returned back to reservoir 16 through the return line 1b. During such operations, the refrigerating machine functions partly as a heat pump and cooperates with the air cooled condenser for air heater 1, so that in the example apparatus hereof, the air in heat exchange relation with the evaporator 3 is first cooled through about 3° C. and is then warmed through about 5° C. in the succeeding air heater 1 which then functions as the condenser of a heat pump.

The change over from cooling operation solely of the system to an operation in which the system functions also as a heat pump, and conversely, is effected by means of the master relay 9 and control relay 11. These relays are so controlled by the thermostat 8 and hygrostat 12 that the predetermined temperature has to be reached in the chill room before the thermostat relay 9 sets up the relay 11 for control by the hygrostat. Hence, only when the predetermined temperature for which the thermostat 8 has been adjusted is reached in the chill room are the circuits for setting up the heat pumping function conditioned for control by hygrostat. In this manner, any undesirable raising of the temperature by the heat pump is prevented. The thermostat 8 controlling relay 9 effects operation of the system as a refrigerating cycle while the hygrostat 12 controls relay 11 effecting operation of the heat pump cycle. The change over from operation of the apparatus to perform the refrigerating cycle, to operation of the apparatus to include the heat

pump cycle, is effected by the automatic changing over of the two condensers 1 and 2 which are connected in parallel. The electrical control shut off valves 5 and 6 are automatically operated to function for interrupting the condensation both in the water cooled condenser 2 and in the air cooled condenser 1, these valves being opened and closed by the relays 9 and 11 which are in turn controlled, respectively, by the thermostat 8 and the hygrostat 12.

In refrigerating plants comprising a plurality of chill rooms it may be desirable to perform an air-conditioning only in one or several of these rooms. In this case, a spring-loaded check valve may be used instead of the electrical shut-off valve 5. Thereby will be obtained an adjustable increase of pressure in the water-cooled condenser 2. Due to this overpressure and by opening the valve 6 during the air-conditioning such a quantity of gas will be conducted to the air heater 4, which suffices, when being condensed, for radiating an amount of heat to the room which is needed to eliminate the refrigerating output of the air-cooler 3 partially or completely.

The time of operation of a refrigerating machine is normally determined by the demand for cold of the chambers connected thereto. The time of operating amounts, if importance is attached to correct humidity of the air, to from 12 to 14 hours per day. With purely thermostatic control, therefore, the idle intervals are about equal in length to the cooling periods.

During the colder season, and particularly in winter, the demand for cold from the cooling plant falls off considerably, as the temperature drop is smaller, corresponding to the smaller difference between the temperature in the chill room and that in the surroundings. In extreme falls of the outside temperature the case may even arise that with known methods and cooling installations no cooling at all by the refrigerating machine takes place. The shorter the running time of the machine, however, the moister does the chill room become, because the removal of moisture from the air in the room only takes place during the cooling. Particularly in a meat-storage room, in consequence of the withdrawal of moisture from the stored contents, after even two hours' interruption of the cooling the relative humidity of the air in the chill room will rise to over 90 per cent; that is, it will reach a value at which the meat deteriorates owing to the formation of mould and the decomposition of protein. The storage of meat for a longer period is only feasible with a constant humidity of the air in the room of at most 75 per cent, that is, a humidity at which the formation of mould is precluded. In recent cooling installations an attempt has therefore been made, by artificially heating the air of the room during the colder season, to replace the absent heat transmission through the insulation from outside, and thereby artificially increase the running time of the refrigerating machine to that value which ensures the air-drying associated therewith. With fully automatic electrical refrigerating installations, electrical energy is as a rule adopted as the source of heat, that is to say, a source of heat which is rather expensive in operation. Thus for example a cooling plant with a refrigerating capacity of 10,000 calories per hour requires a heater of at least 6 kilowatts connected load. On an annual average, such heating is switched on for from 5 to 6 hours per day. For such an installation, therefore, the current consumption per year

amounts to about 11,000 kilowatt-hours. A further disadvantage of the electrical heating of chill rooms consists in the fact that in the vicinity of the heater, in consequence of the unavoidable thermal radiation, the material that is being cooled is adversely affected. There is also the risk that the cooling elements may thaw off during the heating period, a disadvantage that should be obviated, since with the thawing is as-

10 sociated a further increase in the humidity of the air in the room. In the case of electrically heated chill rooms the refrigerating machine is controlled, or in other words switched on and off, by the thermostat, and the heating by the hygrostat. This control is associated with serious disadvantages, because the heating, switched on by means of a hygrostat, first has to heat up the air from 1 to 2 degrees centigrade before the thermostat has overcome its own difference and can switch on the refrigerating plant. During the heating-up time the humidity, which has in any case been raised, is thereby still further increased. Conversely, notwithstanding the relative moisture content of the air having been reached, the 15 air-drying will still continue until the heat accumulated in the heater is discharged. In both cases, therefore, an over-control is effected in respect of air-drying and moistening. Great fluctuations in the humidity of the air are however just as injurious as too high or too low a moisture content.

20 The method described enables the said disadvantages of the known cooling devices of fully automatic electrical refrigerating installations to be eliminated; the temperature and humidity to be maintained exactly at the adjusted value without fluctuations; and the economy of the plant to be improved by from 30 to 50 per cent.

25 What I claim is:

30 1. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 35 in operative relation with said means for cutting out said liquid-cooled condenser; and humidity controlled means in the space to be conditioned without fluctuations; and the economy of the plant to be improved by from 30 to 50 per cent.

40 2. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 45 in operative relation with said means for cutting out said liquid-cooled condenser; and humidity controlled means in the space to be conditioned without fluctuations; and the economy of the plant to be improved by from 30 to 50 per cent.

45 3. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 50 in operative relation with said means for cutting out said liquid-cooled condenser; and humidity controlled means in the space to be conditioned without fluctuations; and the economy of the plant to be improved by from 30 to 50 per cent.

55 4. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 60 in operative relation with said means for cutting out said liquid-cooled condenser; and humidity controlled means in the space to be conditioned without fluctuations; and the economy of the plant to be improved by from 30 to 50 per cent.

65 5. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 65 in operative relation with said means for cutting out said liquid-cooled condenser; and humidity controlled means in the space to be conditioned without fluctuations; and the economy of the plant to be improved by from 30 to 50 per cent.

70 6. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 75 in operative relation with said means for cutting out said liquid-cooled condenser; and humidity controlled means in the space to be conditioned without fluctuations; and the economy of the plant to be improved by from 30 to 50 per cent.

75 7. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned in operative relation with said means for cutting out said liquid-cooled condenser; and humidity controlled means in the space to be conditioned without fluctuations; and the economy of the plant to be improved by from 30 to 50 per cent.

80 8. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 85 in operative relation with said means for cutting out said liquid-cooled condenser; and humidity controlled means in the space to be conditioned without fluctuations; and the economy of the plant to be improved by from 30 to 50 per cent.

85 9. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 90 in operative relation with said means for cutting out said liquid-cooled condenser; and humidity controlled means in the space to be conditioned without fluctuations; and the economy of the plant to be improved by from 30 to 50 per cent.

90 10. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 95 in operative relation with said means for cutting out said liquid-cooled condenser; and humidity controlled means in the space to be conditioned without fluctuations; and the economy of the plant to be improved by from 30 to 50 per cent.

95 11. A system for maintaining constant the temperature and the humidity of a space to be conditioned comprising, in combination, a refrigerating machine including, a refrigerant compressor, a liquid-cooled condenser, and a refrigerant evaporator in heat transfer relation with the space to be conditioned; an air-cooled condenser in heat exchange relation with the space to be conditioned and being connected in parallel with said liquid-cooled condenser; means for controlling the discharge of condensed refrigerant from said liquid-cooled condenser; means for cutting in and rendering active said air-cooled condenser to cause said compressor to function as a heat pump with said air-cooled condenser; temperature control means in the space to be conditioned 100 in operative relation with said means for cutting out said liquid-cooled condenser; and humidity controlled means in the space to be conditioned without fluctuations; and the economy of the plant to be improved by from 30 to 50 per cent.

liquid-cooled condenser; a thermostat in the space to be air-conditioned for effecting the operation of said means for controlling the liquid-cooled condenser; means for cutting in and rendering active said air cooled condenser to cause said compressor to supply hot compressed gases thereto and for cutting out and rendering inactive said air-cooled condenser; an hygostat in the space to be conditioned for controlling said means for cutting in and cutting out said air-cooled condenser; and said thermostat being operatively connected with said hygostat for rendering the latter effective for controlling said means for cutting in and cutting out said air-cooled condenser only when said thermostat has effected operation of the means for controlling said liquid-cooled condenser.

3. A method for air conditioning a chill room by maintaining substantially constant the temperature and the humidity of the air in the room by means of a refrigerating machine, including the steps of; operating the refrigerating machine to perform solely a refrigerating cycle to cool the air in the room to a predetermined temperature; then after attainment of the predetermined temperature, effecting operation of the refrigerating machine to transfer heat therefrom directly to the air in the room until the humidity condition in the room attains a predetermined value or until a predetermined temperature of the air in the room is attained, whichever is prior; and then repeating continuously the aforesaid steps in the sequence recited to maintain substantially constant predetermined temperature and humidity conditions in the room.

4. A system for maintaining constant the temperature and humidity of a space to be conditioned, comprising, in combination; a refrigerating machine including a compressor, a liquid-cooled condenser, a refrigerant evaporator in heat transfer relation with the space to be conditioned, and refrigerant lines connecting said compressor, condenser and evaporator; an air-cooled condenser in heat exchange relation with the space to be conditioned; refrigerant lines connecting said air-cooled condenser with said compressor for supplying hot compressed gas to said air-cooled condenser; means for controlling discharge of condensed refrigerant from said liquid-cooled condenser; a thermostat in the space to be conditioned for controlling the operation of said means for controlling said liquid-cooled condenser; means for cutting in and cutting out said air-cooled condenser; and an hygostat in the space to be conditioned for controlling the operation of said means for cutting in and cutting out said air-cooled condenser.

5. A system for maintaining constant the temperature and the humidity of a space to be conditioned, comprising in combination; a refrigerating machine including a compressor, a liquid-cooled condenser, a refrigerant evaporator in heat exchange relation with the space to be conditioned, and refrigerant lines operatively connecting said compressor, condenser and evaporator; an air-cooled condenser mounted in heat transfer relation with the space to be conditioned; refrigerant lines connecting said air-cooled condenser in parallel with said liquid-cooled condenser; a valve in the refrigerant lines between said liquid-cooled condenser and said evaporator adapted to control delivery of condensed refrigerant from said liquid-cooled condenser; a valve in the refrigerant line to said air-

cooled condenser for closing to cut out and for opening to cut in said air-cooled condenser; a thermostat in the space to be conditioned adapted to control said valve in the refrigerant lines for controlling delivery of refrigerant from said liquid-cooled condenser; and a hygostat in the space to be conditioned for controlling said valve in said lines to said air-cooled condenser.

6. In a method for maintaining constant the temperature and the humidity of a space to be refrigerated by means of a refrigerating machine having a liquid cooled refrigerant condenser, and a refrigerant evaporator and an air cooled refrigerant condenser both in direct heat exchange relation with the air in the space to be conditioned, the steps of; operating the refrigerating machine to evaporate refrigerant in said evaporator to thereby cool the air in the space to be refrigerated to a predetermined temperature; then after attainment of the predetermined temperature, effecting operation of the machine to supply uncondensed refrigerant to said air cooled condenser for condensation therein and transfer of heat to the air in the space to be conditioned until the humidity condition in the room attains a predetermined value or until a predetermined temperature in the room is attained, whichever is prior; and then repeating continuously the aforesaid steps in the sequence recited to maintain substantially constant predetermined temperature and humidity conditions in the room.

7. A system for maintaining constant the temperature and the humidity of a space to be conditioned, comprising in combination; a refrigerating machine including a compressor, a liquid-cooled condenser, a refrigerant evaporator in heat exchange relation with the space to be conditioned, and refrigerant lines operatively connecting said compressor, condenser and evaporator; an air-cooled condenser mounted in heat transfer relation with the space to be conditioned; refrigerant lines connecting said air-cooled condenser in parallel with said liquid-cooled condenser; a valve in the refrigerant lines between said liquid-cooled condenser and said evaporator adapted to control delivery of condensed refrigerant from said liquid-cooled condenser; a valve in the refrigerant line to said air-cooled condenser for closing to cut out and for opening to cut in said air-cooled condenser; a thermostat in the space to be conditioned adapted to control said valve in the refrigerant lines for controlling delivery of refrigerant from said liquid-cooled condenser; and a hygostat in the space to be conditioned for controlling said valve in said lines to said air-cooled condenser, the thermostat being operatively connected with said hygostat to render the latter inoperative when said valve is opened for maximum discharge from said liquid-cooled condenser and to render said hygostat operative when said valve is operated to control discharge from said condenser.
